UNITED STATES PATENT OFFICE.

BEN WEINBERG, OF BALTIMORE, MARYLAND.

DESIGN FOR A SHOW-CASE.

SPECIFICATION forming part of Design No. 31,758, dated October 31, 1899.

Application filed September 9, 1899. Serial No. 730,030. Term of patent 7 years.

To all whom it may concern:

Be it known that I, BEN WEINBERG, a citizen of the United States, residing at Baltimore, in the State of Maryland, have invented 5 and produced a new and original Design for Show-Cases, of which the following is a specification.

The leading features of my design for a display or show case consist of a circular base 10 and a case mounted on said base which in side elevation is circular in form and in plan has two straight parallel sides, the design as a whole having a similar appearance to a watch-case mounted vertically on a circular base.

15 Figure 1 is a front side elevation of my design, and Fig. 2 a plan view of same.

In the drawings, A designates a flat circular base in a horizontal plane; B, a shallow

circular case mounted vertically or upon its circumferential edge and a fillet interposed 20 between the lowermost portion of said edge and the said circular base.

The circumference or circular edge of the case near the top has a ring f, which incloses a milled head or stem. 25

Having thus described my design, what I claim is—

The design for a show-case as herein shown and described.

In testimony whereof I affix my signature 30 in the presence of two witnesses.

BEN WEINBERG.
